UNITED STATES PATENT OFFICE

FRANK E. CRAIG, OF ASTORIA, OREGON, ASSIGNOR OF ONE-FOURTH TO JAMES W. LOVELL, OF ASTORIA, OREGON

LIFEBOAT HOOK

Application filed February 29, 1932. Serial No. 595,893.

The invention relates primarily to a releasable hook for connecting either end of a lifeboat with a block and tackle suspended from a conventional davit. Such hooks are subjected to extremely rough usage whether used in launching lifeboats, or for launching other small boats carried by larger crafts, particularly during rough weather, and quite serious accidents have occurred from failure of the conventional hooks at crucial moments, one of the most serious hazards being the fact that the pivot of the releasable hook, may become lost or broken, prematurely releasing one end of the boat with disastrous results.

It is the object of my invention to provide a new and improved hook of the type set forth, which will readily withstand all rough usage to which subjected, and provided with safety means for preventing pulling of the pivoted hook from the casing and for carrying the hook-supported load if the hook pivot should become broken or lost.

With the foregoing in view, the invention resides in the novel subject matter herein after described and claimed, description being accomplished by reference to the accompanying drawing.

Fig. 1 is a perspective view of a hook constructed in accordance with the invention.

Fig. 2 is a vertical sectional view showing the pivoted hook held in operative position.

Fig. 3 is a view similar to Fig. 2 but showing the manner in which the safety means holds the pivoted hook even when its pivot is removed.

A preferred construction has been shown and will be specifically described, with the understanding however that variations may be made within the scope of the invention as claimed. Furthermore, while the primary intent of the invention is for use as a lifeboat hook, it may obviously be employed for other purposes also, wherever a positive-holding, quick-releasing hook is advantageous.

The numeral 5 on the drawing denotes a cast-metal casing whose upper end is provided with a yoke 6 for connection with a block and tackle, while the lower end of said casing

is formed with a throat 7 to receive a load-supporting eye or ring, such as a ring-bolt of a lifeboat. Along its lower end 8 and one vertical edge 9, the casing 5 is open, but along the lower portion of its other vertical edge, 55 it is closed by an integral web 10. Near the open edge 8, upper and lower lugs 11 and 12 are provided integrally connected to the opposite side walls of the casing.

A pivoted hook 13 is provided, said hook 60 having a bill 14 which normally extends across the throat 9 to engage the eye, ring-bolt or the like. The pivot 15 of this hook 13 is between the throat 7 and the lower end of the web 10, and said hook is provided with 65 an upstanding shank 16 which projects upwardly beyond the pivot 15 and is spaced inwardly to a slight extent from said web 10.

A locking lever 17 is fulcrumed at 18 in the casing 5 and at one end normally abuts 70 the inner edge of the shank 16 to hold the hook 13 in operative position, said locking lever being quickly moved to this position by a coiled spring 19 when the hook 13 is closed. Preferably, the upper extremity of 75 the shank 16 is obliquely cut as shown, and the lever 17 is provided with a V-shaped notch 20 receiving said extremity of said shank. Either contact of the upper wall of the notch 20 with the shank 16, or contact of lever 17 with lug 11, or both, may be relied upon to limit the movement of said lever under the influence of the spring 19, and for releasing said lever when it is desired to release the load, a pull chain or the like 21 is 80 provided.

Safety means are employed to prevent pulling of the hook 13 from the casing 5, and to carry the weight of the hook-supported load, in case the pivot 15 of the hook 13 85 should become broken or lost. This safety means preferably comprises an abutment 22 carried by the casing 5 and a socket 23 in the hook shank 16, said abutment and socket being loosely interfitted when hook 13 is in operative position, as shown in Fig. 2. In case the pivot 15 should become lost or broken however, the hook 13 will descend slightly until the upper edge of the socket 23 contacts 90 with the abutment 22, whereupon further 100

downward movement of the hook will be prevented, so that the hook 13 and the abutment 22 will then carry the entire load suspended from said hook, overcoming dangers which 5 now exist in connection with conventional lifeboat hooks. When the hook is being supported by the pin 22 as seen in Fig. 3, the lug 12 prevents insufficient swinging of said hook to allow disengagement of the safety 10 means 22-23, until the latch 17 is released.

When the hook shank is properly held by the lever 17, it is impossible for the hook 13 to become released even with severely 15 rough usage, and while said hook is under load, it cannot be released by pulling upon the chain 21. As soon as the load is taken from the hook however, for instance, when the life-boat comes to rest upon the water, 20 pulling of chain 21 will release the hook and free the boat or other load.

It will be seen from the foregoing that a new and advantageous construction has been provided, and while the details disclosed have proven of great advantage, attention is 25 again invited to the fact that variations may be made. For instance, the pivot 15, fulcrum 18 and abutment 22 are each preferably formed from a heavy screw held against accidental release by a locking screw such as 30 24, but such details are not essential.

I claim:

1. A lifeboat hook comprising a casing having a throat in its lower end, a load-supporting hook pivoted in said casing, said 35 hook having a bill extending across said throat and being provided with an upwardly projecting shank at one side of said throat, latch means in the casing normally abutting said shank to prevent swinging of the hook 40 to released position until said means is released, safety means for preventing pulling of the hook from the casing and for carrying the hook-supported load if the hook pivot should become broken or lost, and means fixedly 45 carried by said casing to abut the hook and prevent swinging thereof to free said safety means until said latch means is released.

2. A lifeboat hook comprising a casing having a throat in its lower end, a load-supporting hook pivoted in said casing, said hook having a bill extending across said 50 throat and being provided with an upwardly projecting shank at one side of said throat, latch means in the casing normally abutting said shank to prevent swinging of the hook 55 to released position until said means is released, interfitting means carried by said casing and said hook for preventing pulling of the hook from the casing and for carrying the 60 hook-supported load if the hook pivot should become broken or lost, and means fixedly carried by said casing to abut the hook and prevent such swinging thereof as to disengage 65 said interfitting means until said latch means is released.

3. A lifeboat hook comprising a casing having a throat in its lower end, a load-supporting hook pivoted in said casing, said hook having a bill extending across said throat and being provided with an upwardly projecting shank at one side of said throat, latch means in the casing normally abutting said shank to prevent swinging of the hook to released position until said means is released, an interfitting abutment and socket, one carried by the casing and the other by the hook shank for preventing pulling of the hook from the casing and for carrying the hook-supported load if the hook pivot should become broken or lost, and a stop fixedly carried by the casing in position to abut the hook bill to prevent such swinging of the hook as to disengage 70 said abutment and socket until said latch means is released.

In testimony whereof I affix my signature.

FRANK E. CRAIG.
